DESIGN FOR A TEXTILE PILE FABRIC

John J. Repp, Philadelphia, Pa., assignor to Collins & Aikman Corporation, Philadelphia, Pa., a corporation of Delaware

Application March 8, 1941, Serial No. 99,439

Term of patent 14 years

To all whom it may concern:

Be it known that I, John J. Repp, a citizen of the United States, residing at 5228 Schuyler Street, Philadelphia, Philadelphia County, State of Pennsylvania, have invented a new, original, and ornamental Design for a Textile Pile Fabric, of which the following is a specification, reference being had to the accompanying drawing, forming part thereof which shows a plan view of a piece of textile pile fabric embodying my new design.

The design comprises woven parallel, relatively broad, straight stripes or ribs, the surface of each of which is arcuated convexly, the crown portion being soft and the low portions being firm, the stripes or ribs being separated by thin lines created by the omission of pile.

I claim:

The ornamental design for a textile pile fabric, as shown and described.

JOHN J. REPP.
